UNITED STATES PATENT OFFICE.

WALTER C. KERN AND WILLIAM YOUNG, OF LEAVENWORTH, KANSAS.

DUMP-BODY HOIST.

1,328,837.

Specification of Letters Patent. Patented Jan. 27, 1920.

Application filed July 3, 1918. Serial No. 308,640.

To all whom it may concern:

Be it known that we, WALTER C. KERN and WILLIAM YOUNG, both citizens of the United States, and residing at Leavenworth, 5 in the county of Leavenworth and State of Kansas, have invented certain new and useful Improvements in Dump-Body Hoists, of which the following is a specification.

Our invention relates to certain new and 10 useful improvements in hoists for raising and lowering the dump bodies of trucks, trailers and wagons and in its generic nature the invention has for its object to provide an apparatus which will be positive in its 15 operation, strong and durable in its construction and which will effectively serve its intended purposes. In its more subordinate 20 nature, the invention comprises a standard or support in which there is vertically slid- able a carriage to which the end of the dump body to be elevated is connected, there being a cable and pulley mechanism provided for sustaining the elevator carriage in its different 25 positions of elevation and there being further provided a ratchet and pawl mech- anism for effecting the upward movement of the elevator carriage, means being pro- vided for automatically disconnecting the pawl from the ratchet at the extremity of 30 the upward movement of the carriage and restoring the pawl to engagement with the ratchet after the carriage has been again lowered, the lowering of the carriage being controlled by the pulley and cable devices. 35 In its more detail nature, the invention includes those novel features of construction, combination and arrangement of parts, all of which will be first fully described and then be specifically pointed out in the ap- 40 pended claims, reference being had to the accompanying drawings, in which:—

Figure 1 is a side elevation illustrating the invention in use.

Fig. 2 is an enlarged vertical cross sec- 45 tion, parts being broken away showing the invention.

Fig. 3 is a central vertical section and part elevation of the device, parts being broken away.

50 Fig. 4 is a horizontal section taken sub- stantially on the line 4—4 of Fig. 2.

Fig. 5 is a detail horizontal section on substantially the line 5—5 of Fig. 2.

55 Fig. 6 is a detail view somewhat diagram- matic, showing a modified form of com- pounding lever mechanism for raising the movable ratchet.

Fig. 7 is a detail diagrammatic view of a modification of the invention.

Fig. 8 is a detail elevation of a modified 60 construction employed for connecting the elevator carriage with the truck body.

Fig. 9 is a detail cross section showing a modified arrangement of the ratchets and 65 carriage in the vertical upright guides.

Fig. 10 is a detail view of a modification of the ratchet operating mechanism whereby the hand lever may be moved in a plane parallel with the length of the vehicle.

In the drawings, in which like numerals 70 and letters of reference indicate like parts in all of the figures, 1 represents the frame of the vehicle and 2 the tiltable dump body while 3 indicates the hoist which constitutes our invention. The hoist is composed 75 of a pair of channel irons 3—3, secured at their base to the chassis of the vehicle in any desired and effective way and connected together at their tops by a cross bar 9 which carries an idler pulley 10 over which the 80 sustaining cable 11 passes.

4 is the elevator carriage which may be grooved to fit over the longitudinal edges of the channel beams 3 (see Fig. 5) and be guided thereby, or the arrangement shown 85 in Fig. 9 may be employed. The carriage includes a bracket 5 and supports a cross bolt 6 on which the lifting and holding pawls 7 and 8 respectively are mounted.

The carriage 4 may be provided with eyes 90 12 and 15 to which the ends of the cable 11 are connected, the cable 11 being passed around the drum 13 which is mounted on the shaft 14 that is in turn suitably journaled in bearings on the chassis of the vehicle, a 95 crank 18 being provided by which the shaft 14 may be manipulated, there being also pro- vided a ratchet 16 and pawl 17 to prevent backward motion of the shaft 14 as the carriage 4 is being elevated.

100 19 designates a fixed ratchet mounted in one of the channel beams 3 and having a throw-out projection 27 for a purpose pres- ently explained. 20 designates the oper- ating or movable ratchet which is also 105 mounted in the channel beam adjacent to the ratchet 19 and the ratchet 20 may be held for vertical movement by pin and slot arrangements 22—21, as shown in Figs. 2 and 5 of the drawings. The ratchet 20 may 110 be of T shape in cross section and inter- engaging the ratchet 19 and a bar 3^x secured to the channel member 3, as shown in Fig. 9. The lower end of the ratchet 20 rests

on a bell crank lever 23 which is fulcrumed at 24 and linked at 25 to the operating lever 26. The ratchet 20 is also provided with a throw-out projection 27, the throw-out projections 27 of the ratchets 19 and 20 serving to throw the pawls 7 and 8 beyond the dead center so that when the carriage 4 is elevated to its maximum height the pawls 7 and 8 will be disengaged from the ratchets 5 and fall over, as shown in dotted lines, thus leaving the carriage 4 free to be lowered again by means of the handle 18, the pawl 17 being disengaged from the ratchet 16 when it is desired to lower the carriage 4. 10 15 20 25 30 35 40 45 50 55 60 65 70 75 80 85 90 95 100 105 110 115 120 125

In the preferred embodiment of the invention, the pawls 7 and 8 are hanging pawls, that is, the weight of the carriage 4 hangs by the pawls on the ratchets. If desired, an arrangement of ratchets such as diagrammatically illustrated in Fig. 7 may be employed in which the ratchet engaging end of the pawl 7^a is below the pivotal axis and thus the weight of the carriage rests downwardly on the pawl and ratchet rather than hanging from above on the same as in the first form. Instead of employing the bell crank 23, lever 26 and link 25, the lever 26^a may have its action compounded through rocking levers 25^a—23^a, as shown in Fig. 6, or other modifications of the invention, as will readily occur to the skilled mechanic, may be made without departing from the spirit of the invention.

30 designates an eye on the bracket 5 which is connected by a cable or rod 31 to the bracket member 32 of the dump body 2 or any other suitable connection between the dump body and the carriage 4 may be employed whereby as the operator rocks the lever 26 (the carriage 4 being in the lowermost position with the body 2 down, as shown in dotted lines in Fig. 1) he causes the ratchet 20 to be raised and lowered by a succession of movements, the weight of the ratchet being ordinarily sufficient to cause it to drop to its lowermost position after being elevated by the operation of the lever 26. As the ratchet 20 is rocked up and down to raise the carriage 4, the holding pawl 8 will engage its ratchet 19 during the time the ratchet 20 is falling and thus hold the carriage 4 in its elevated positions. Having elevated the tank body 2 sufficiently to dump the contents, the operator, by manipulating the crank 18 a few times more, 60 will cause the pawls 7 and 8 to be engaged by the throw-out projections 27 and thus tilt the pawls 7 and 8 sufficiently to cause the center of gravity to fall to the right of the vertical axis of the bolt 6 in Fig. 2 (see dotted lines at the upper portion of that

figure) and thereby cause the pawls to rock out of engagement with the ratchets. The operator then releases the pawl 17, while grasping the handle of the crank 18 and lowers carriage 4. As the carriage reaches 70 its lowermost position, the projection 29 will restore the pawls to their ratchet engaging position and the parts will be ready for further operation when desired.

Instead of the levers 23, 25 and 26 arranged as shown in Fig. 2, the mechanism employed in Fig. 10 may be used. By reference to that figure it will be seen that to the lower end of the ratchet is connected a link 20^a with an articulated joint, the link 80 20^a having a pin 20^b to enter the slot 23^b of the heel of the lever 23, the lever 23 being linked at 25 to the arm 26^a of a gear segment 26^b which is mounted on a stub shaft 26^c journaled in suitable bearings (not shown) 85 and meshing with a pinion 26^d on a crank shaft 26^e to the end of which a crank lever 26^f may be attached so that by rocking the crank lever the necessary motion will be imparted to the lever 23 to effect the required reciprocations of the ratchet 20.

Instead of directly connecting the body 2 to the carriage 4, as shown in Fig. 1, an evener bar 33 is provided which is connected by the cable 31 to the dump body and which 95 is itself sustained by cables 34 which pass over sheaves 35 and have their ends fastened in any suitable manner (not shown) to the frame of the vehicle so as to anchor the said ends. The sheaves 35 are carried 100 by an evener bar 36 which is secured to the carriage 4, as indicated, so as the carriage 4 is raised, the body 2 will be elevated a greater distance than the elevation of the carriage 4, due to the pulley and cable connections, etc.

Changes in the details of construction, combination and arrangement of parts will readily suggest themselves to those skilled in the art and we do not wish to be understood as limiting ourselves to the precise details of construction shown and described.

What we claim is:—

1. A dump body hoist comprising a standard having guides, a carriage vertically movable on said guides, a pulley and cable mechanism for lowering said carriage, and a ratchet and pawl device for raising said carriage, said carriage being adapted to be connected with the dump body to raise and lower the same.

2. In apparatus of the class described, the combination with the vehicle, the dump body pivoted thereon, of a hoist mounted on the vehicle and comprising vertical standards, 125 a carriage mounted on said standards for vertical movement, pulley and cable mechanism by which said carriage may be raised and lowered, a back check pawl and ratchet mechanism coöperative with said pulley and 130

cable mechanism, a ratchet and pawl device for raising said carriage and a connection between said carriage and dump body.

3. A dump body hoist comprising a standard having guides, a carriage vertically movable on said guides, a pulley and cable mechanism for lowering said carriage, and a ratchet and pawl device for raising said carriage, said carriage being adapted to be connected with the dump body to raise and lower the same, said ratchet and pawl mechanism comprising a stationary ratchet coöperating with said standard, a pawl on the carriage coöperating with said stationary ratchet, a reciprocable ratchet, another pawl on said carriage coöperative with said reciprocable ratchet and means for reciprocating said reciprocable ratchet.

4. In apparatus of the class described, the combination with the vehicle, the dump body pivoted thereon, of a hoist mounted on the vehicle and comprising vertical standards, a carriage mounted on said standards for vertical movement, pulley and cable mechanism by which said carriage may be raised and lowered, a back check pawl and ratchet mechanism coöperative with said pulley and cable mechanism, a ratchet and pawl device for raising said carriage, a connection between said carriage and the dump body, said ratchet and pawl mechanism comprising a stationary ratchet coöperating with said standard, a pawl on the carriage coöperating with said stationary ratchet, a reciprocable ratchet and another pawl on said carriage coöperative with said reciprocable ratchet, and means for reciprocating said reciprocable ratchet.

5. A dump body comprising a standard having guides, a carriage vertically movable on said guides, a pulley and cable mechanism for lowering said carriage, a ratchet and pawl device for raising said carriage, said carriage being adapted to be connected with the dump body to raise and lower the same, said pawl and ratchet mechanism comprising ratchets carried by the standard, pawls carried by said carriage, means for operating said ratchet and pawl mechanism to raise the carriage, and means for disconnecting the pawls from the ratchets after the carriage has been raised.

6. In apparatus of the class described, the combination with the vehicle, the dump body pivoted thereon, of a hoist mounted on the vehicle and comprising vertical standards, a carriage mounted on said standards for vertical movement, pulley and cable mechanism by which said carriage may be raised and lowered, a back check pawl and ratchet mechanism coöperative with said pulley and cable mechanism, a ratchet and pawl device for raising said carriage, a connection between said carriage and dump body, said

pawl and ratchet mechanism comprising ratchets carried by the standard, pawls carried by said carriage, means for operating said ratchet and pawl mechanism to raise the carriage, and means for disconnecting the pawls from the ratchets after the carriage has been raised.

7. A dump body comprising a standard having guides, a carriage vertically movable on said guides, a pulley and cable mechanism for lowering said carriage, a ratchet and pawl device for raising said carriage, said carriage being adapted to be connected with the dump body to raise and lower the same, said pawl and ratchet mechanism comprising ratchets carried by the standard, pawls carried by said carriage, means for operating said ratchet and pawl mechanism to raise the carriage, means for disconnecting the pawls from the ratchets after the carriage has been raised, and means for restoring the pawls into engagement with the ratchets when the carriage has been lowered.

8. In apparatus of the class described, the combination with the vehicle, the dump body pivoted thereon, of a hoist mounted on the vehicle and comprising vertical standards, a carriage mounted on said standards for vertical movement, pulley and cable mechanism by which said carriage may be raised and lowered, a back check pawl and ratchet mechanism coöperative with said pulley and cable mechanism, a ratchet and pawl device for raising said carriage, a connection between said carriage and dump body, said pawl and ratchet mechanism comprising ratchets carried by the standard, pawls carried by said carriage, means for operating said ratchet and pawl mechanism to raise the carriage, means for disconnecting the pawls from the ratchets after the carriage has been raised, and means for restoring the pawls into engagement with the ratchets when the carriage has been lowered.

9. A dump body hoist comprising a pair of channel irons forming a standard, a carriage vertically slidably guided between said irons, a pulley and cable mechanism connected with said carriage, a fixed ratchet and a movable ratchet mounted in said standard, pawls mounted on said carriage coöperating with said ratchets for raising said carriage and holding it in its different positions, a lever actuated means for reciprocating one of said ratchets to raise the carriage, and means for throwing the pawls out of engagement with the ratchets when the carriage is at its uppermost position and restoring the pawls again to engage with the ratchets when the carriage is in the lowermost position.

WALTER C. KERN.
WILLIAM YOUNG,
